UNITED STATES PATENT OFFICE.

LAWRENCE W. LUELLEN, OF MOUNTAIN LAKES, NEW JERSEY.

SYSTEM OF MOBILE ARMAMENT.

Application filed May 26, 1917. Serial No. 171,158.

Hitherto, it has been suggested to mount ordnance of the smaller caliber upon railroad cars for quick transportation along the tracks, so that by reason of this mobility, 5 the position of the guns may be quickly shifted as exigencies may arise. This has proven feasible where guns of light weight have been used because the presently-used tracks and cars are of sufficient strength to 10 withstand the shocks incident to the firing of such guns.

Where armament of the large caliber, such as heavy mortars and large caliber rifles are concerned, the present railroad systems are 15 inadequate in point of strength to accomplish this desired object. It has been necessary, therefore, to provide supplemental supporting means so designed as to cooperate with the car body upon which the heavy 20 ordnance is mounted to take up the shock of the recoil of the gun.

One means for accomplishing this object has been fully disclosed in Patent No. 1,244, 431. In the patent referred to, we disclose 25 the use of concrete supporting bases located beneath the road bed at suitable intervals or at strategic points along the railroad, these bases cooperating with specially designed car bodies, so that such car bodies 30 bearing the heavy ordnance can be quickly brought into proper supported position upon the foundation to enable the gun to be fired without displacement either from the car body or the wheeled trucks therebeneath.

While my invention relates to the same general subject-matter, one of its particular objects is to provide a car body, of such construction as to adapt it to cooperate with a concrete foundation or with supplemental 40 supporting rails arranged longitudinally of the railroad track for the purpose of absorbing the shock incident to the firing of the gun. In this manner, a car with a wider range of usefulness is obtained.

According to one phase of my present invention, I provide the concrete foundation with upward extensions at either side of the track forming as it were a channel like concrete reinforced structure into which the 50 car body is received, means being provided for positively locking and firmly holding

the car body against displacement when properly positioned therein.

According to another phase of my invention, I provide supplemental supporting rails 55 also arranged at intervals along the main track of the railroad at desired points, these supplemental rails being preferably located adjacent to but outwardly of the main tracks of the railroad, thus constituting as it were 60 short rail sections of wider gage than that of the normal railroad track. These rails are preferably made of greater cross section than the regular tracks, so as to afford 65 strength and increased supporting ability. 65 Along the sides of the car body and immediately beneath the surmounted ordnance are provided side supporting members which are wedged downwardly into cooperation 70 with the supplemental supporting rails when 70 the car is brought thereover into firing position, so that the greater shocks, which would be destructive to the ordinary running gear of the car, are properly and efficiently taken up at these lateral points of support. 75

Referring to the accompanying drawings, in which I have illustrated by way of example one preferable embodiment of my present invention,

Figure 1 is a view in side elevation of a 80 fragmentary portion of a railroad, a concrete supporting foundation therebeneath, supplemental supporting rails adjacent the main tracks and a car of my improved construction carrying a heavy ordnance rifle and 85 arranged in cooperative relationship preparatory to gun fire.

Figure 2 is a top view of Figure 1, illustrating in plan the vertical extensions of reinforced concrete to which the sides of the 90 car may be locked, a fragmentary portion only of the car body being shown.

Figure 3 is a transverse sectional view taken on line III—III of Figure 1, showing the manner in which the car body is 95 brought into cooperative supporting relationship with the supplemental rails and the laterally arranged reinforced concrete supports.

Figure 4 is a view in side elevation on an 100 enlarged scale of a portion of the car body and the supplemental supporting rails, parts

being shown broken away and sectioned in order to more clearly illustrate the manner in which the car body is brought into its definite and predetermined location with respect to the supplemental supporting rails.

Figure 5 is an enlarged detail of the operating means employed for forcing the movable wedge actuated supporting members of the car into engagement with the supplemental supporting rails.

Figure 6 is a view in vertical cross-section of a fragmentary portion of the car body and the supplemental supporting rails taken on line VI—VI of Figure 5 and also showing the means employed for locking the car body to the concrete supporting foundations.

Figure 7 is a similar view in detail taken on lines VII—VII of Figure 5 showing the car body in position upon the supplemental supporting rails.

Figure 8 is an enlarged detail of the operating means shown in Figure 5 as employed for producing the wedging action referred to.

Figure 9 is a cross sectional view of a supporting supplemental rail.

Figure 10 is a similar view of Figure 1 excepting the supplemental supporting rail is arranged in a plane parallel to the plane of the main rails and illustrating that phase of the invention where no additional supporting foundation is used and where the car may be moved along the track by the shock of recoil incident to the firing when the gun is longitudinally of the car.

Figure 11 is an end view in front elevation of Figure 10.

Figure 12 is a fragmentary view on an enlarged scale of a modified means for operating the movable supports or shoes arranged at the sides of the car body.

Figure 13 is a view in cross-section taken on line XIII—XIII of Figure 12.

Figure 14 is a small detail view for the purpose of illustrating the curvature of the tracks and rails.

In detail the ties 1, rails 2, trucks 3, axles 4, and wheels 5 are all of conventional and well understood construction. 6 indicates the car body upon which is mounted the heavy ordnance and which for the purpose of illustration takes the form of a large caliber rifle 7. The car body is provided with side beams 8, extending longitudinally along its sides and upon each of which side beams, in transversely tapered guideways 8^a, are mounted a series of similarly formed movable supporting members or shoes 9 and a series of supplemental wheels 10, which are arranged to cooperate with the supplemental tracks 11, the latter being arranged at desired points where the ordnance is to be used. The supplemental wheels 10 are journaled upon axles 12 and are mounted within suitable slots 13 provided in the side

beams of the car. The mountings of these wheels are unequally spaced, as illustrated, and are employed for facilitating the movement of the car body to its proper location upon the supplemental rails, the latter being 70 provided with slight circular depressions 14, similarly spaced, so that when the car is properly positioned, that is to say when the wheels are brought into alignment with the depressions, the former will occupy the latter. The mounting of these supplemental wheels enables them to run along the supplemental rails to facilitate the transportation of the car to its proper position for gun fire, the car body being slightly lifted 80 from the main trucks 3 until the wheels are brought coincident with the rail depressions which they occupy, whereupon the weight is relieved therefrom in a manner thought to be well understood. The ends 15 of the supplemental rails 11 are chamfered off or tapered to permit the wheels to readily engage them when brought into cooperation therewith.

In the embodiment of my invention, as 90 illustrated in Figures 1 to 8, inclusive, I propose to firmly lock the car body in position for gun fire and additionally support it in such a way as to enable the gun to be fired laterally of the car. To accomplish 95 this, I provide a concrete foundation beneath the track and extending upwardly at the sides thereof, into supporting pillars or extensions 36. This concrete construction is reenforced by the use of metal beams or 100 plates 37. This forms a channel or groove for the reception of the car body and when the car body has been properly positioned therein upon the supplemental supporting rails, the same is positively locked in position by means of the bolts 38 and cooperating nuts 39, one end of each bolt being held by a bracket 40 fast to an angularly faced plate 41 anchored in position by the tie bolts 42 embedded in the concrete foundation. 110 Anchoring members 43 are employed and extend across between the angular plate 41 and the side portion of the car body, these being held in place by suitable bolts 38. By this means the car body is secured in place 115 and adequately supported so as to withstand and take up any thrust or strain due to gun fire laterally of the car. If desired, I may provide the car body with a rounded projecting bead or edge 44 (see Figures 6 and 120 7), which will fit within corresponding semi-circular depressions in the anchoring members 43. This constitutes a very stable abutment for the anchoring members when they are being forced home during the locking 125 operation.

In the embodiment of my invention, as 130 illustrated in Figures 1 to 4, inclusive, the supplemental supporting rails are in the form of I-beams having a channel-like

groove centrally located throughout their length with angular faces 45 in parallel relation to the coincident angular faces 46 of the shoes 9, thus affording friction surfaces for these parts when they are brought into co-operative relation, and offer great resistance to relative movement of the car body upon the track. It will be observed that these supplemental supporting rails in this embodiment of the invention are on an incline. The object of this is to facilitate locating the car body properly within and on the emplacement.

When the car body has been brought into proper position, at points remote from the concrete base the supplemental supporting members or shoes 9 are forced downwardly against the supplemental rails 11 to add the required rigidity to the car body so as to withstand the shock of recoil when the gun is fired. These shoes 9 are of U-shaped construction (see Figure 6) and are independently mounted in suitable openings or cavities provided in the side beams 8 between the supplemental wheels 10. In order to accomplish the movement of the shoes into co-operative relation with the supporting rails, they are provided with interior inclined slots 16, with which cooperate wedge like members 17, the latter being connected to a member 18 so that they may all be operated in unison. One extremity of the member 18 has a sliding bearing in the side beams 8 at 19, while its opposite extremity is provided with a worm or screw-thread 20. Cooperating with the threaded end 20 is an interiorly threaded gear 21 mounted between an abutment 22 and the surface 23 of the cavity formed in the side beam for its accommodation. The gear member 21 is provided with exterior teeth, which engage a gear 24 mounted upon a shaft 25 having a bearing in a standard 26. This shaft 25 is provided with a hand wheel or gear 27 by means of which the gears and member 18 may be operated to cause the wedges 17 to lower and raise the shoes or supporting members 9. In order to raise the shoe members 9, the wedges 17 are provided with lateral extensions 28 which operate in slots 29 of the shoes (see Figure 6) so that when the wedges are raised, the shoes will be caused to rise also.

When the embodiment of the invention above described is employed as a fixed mount, it is not necessary that the shoes 9 be depressed to such an extent as would disengage the wheels 10 from the depressions 14. However, when the same is used as a sliding mount, the shoes will be forced downwardly sufficiently to withdraw the wheels 10 entirely from said depressions, thus preventing said wheels, when riding up out of the depressions, from lifting the shoes away from contact with the supplemental rails.

Instead of operating the supplemental

supporting members or shoes simultaneously by a single operating means, I may, where found desirable, employ separate operating means for each shoe. I have illustrated such mechanism in Figures 12 and 13. This mechanism comprises a threaded bolt 30, one extremity of which is swivelly mounted at 31 in a yoke piece 32 extending rearwardly from the side beam of the car. The opposite extremity of this bolt is formed square or hexagonal as at 33 for the accommodation of a proper wrench or tool for turning the same. Mounted upon this bolt and in screw-threaded connection therewith and guided within suitable openings provided therefor, is a nut 34 having inclined wings or extensions 35 (see dotted outline in Figure 13), which cooperate with inclined grooves in the shoe 9. From this it will be obvious that as the screws are turned, the nuts will be caused to move therealong moving the shoes either toward or away from the supplemental rails according to the direction of rotation.

Referring to the embodiment of my invention as illustrated in Figures 10 and 11, here I propose to use the car illustrated in the other figures and as above described in connection with supplemental supporting rails only. In this embodiment, the main rails 2 and the supplemental supporting rails 11 are curved laterally for about 90° of a circle on a quarter of a mile radius (see Figure 14), so that the car may be moved in an arc from point to point as necessity arises to enable the gun to be fired which firing is done longitudinally of the car. Prior to firing, the shoes 9 are brought into engagement with the supplemental supporting rails 11 and the force of the recoil of the gun transmitted to the car causes it to slide along the tracks, the supplemental shoes offering resistance to this movement. Of course, in this construction, the gun can only be fired at a target from a point on the track that is approximately tangential to a circle, whereas in the construction illustrated in Figures 1 to 4, inclusive, where a fixed base is employed to which the car may be effectively locked in immovable position, the gun may be fired laterally of the car or at any desirable angle to the longitudinal axis thereof or longitudinally of the car. The gun when secured to the concrete base can be fired rapidly and accurately at the right times and without necessitating the repositioning the car for range as would be necessary if the car shifted its position after firing.

Should it be desired for any cause to promptly move the car body away from its position within the concrete foundation in the absence of a locomotive, I provide at its forward end one or more compressed air cylinders 47, provided with a piston 48, which may be forced outwardly by com-

pressed air admitted to the port 49, this piston engaging an abutment 50, which may be of re-enforced concrete construction formed integral with the emplacement if desired. In operation the piston engaging the abutment will dislodge the supplemental wheels 14 from the depressions in the supplemental rails 11 and the car may be pushed back with sufficient impetus along the tracks from the emplacement to carry the same well away from its original position.

The general flexibility of the system described will be noted and appreciated by those skilled in the art. The supplemental rails may be very readily transported and expeditiously mounted in operative position while the reenforced concrete supporting foundations may be previously built at strategic points along the railroad.

While I have illustrated certain preferred embodiments of my invention, I do not wish to be limited in respect to details, but desire to cover the principles disclosed in whatever form they may be embodied.

Having thus described my invention, I claim:

1. The combination of a railroad track, including a main track, a car body, wheeled trucks therefor, a gun mounted thereon, supplemental track supports adjacent the main track, adapted to withstand recoil shocks incident to gun fire and means on the car body adapted to be brought into supported position upon the supplemental tracks to position the car for gun fire and to transmit said shocks.

2. The combination of a railroad track, including a car body, a gun mounted thereon, said car body being provided with wheeled trucks, supplemental supporting tracks adjacent to the main track and laterally disposed with respect to said car body and means carried by the car body for interengaging the supplemental supporting tracks, whereby the shock incident to the firing of the gun is in part taken up by the supplemental supporting tracks and the wheeled trucks relieved of such shocks.

3. The combination of a railroad track, a car including a body and wheeled trucks therefor, a gun mounted on said car body, supplemental grooved track supports laterally disposed with respect to said car body, said body being provided with depending strain transmitting members adapted to engage in the grooves of the track supports when the car is moved thereover to relieve the wheeled trucks of the strain of recoil shock.

4. In combination with a railroad track, supplemental supporting tracks disposed at intervals therealong, said supplemental supporting tracks running parallel with the

main track and adjacent thereto, a car body having a gun mounted thereon and provided with wheeled trucks adapted to move over the railroad, supplemental supporting wheels journaled beneath the car body and in position to engage the supplemental tracks and adjustable body supports for engaging the supplemental tracks.

5. In combination with a railroad track, supplemental car body supports mounted at intervals along said track and adjacent thereto, a car body, a gun mounted thereon, wheeled trucks for said car body adapted to transport the same over the main tracks of the railroad and supplemental wheels at both sides of the lateral extremities of the car body adapted to cooperate with the supplemental supports for the purpose of assisting in the dissipation of shock incident to the firing of the gun.

6. In a system of mobile armament, a railroad comprising a main track, supplemental tracks at intervals therealong and mounted adjacent to the main track, a car body with a gun mounted thereon provided with wheeled trucks cooperating with the main track to transport the same, supplemental wheels suitably journaled in the car body intermediate the wheel trucks adapted to cooperate with the supplemental supporting rails to assist in the positioning of the car body, and adjustable body supports for engaging the supplemental supporting rails.

7. In a system of mobile armament, a railroad comprising a main track, supplemental tracks having inclined depressions at intervals therealong and mounted adjacent to the main track, a car body with a gun mounted thereon provided with wheeled trucks cooperating with the main track to transport the same, supplemental wheels suitably journaled in the car body intermediate the wheel trucks adapted to cooperate with the supplemental supporting rails and to seat within the inclined depressions to assist in the positioning of the car body, and adjustable body supports for engaging the supplemental supporting tracks.

8. In a system of mobile armament, the combination of a railroad including a main track and supplemental supporting tracks disposed at intervals therealong, running gear for said car body including wheeled trucks, supplemental wheel supports laterally disposed on said car body and cooperating with said supplemental tracks and stress distributing supports located adjacent the supplemental tracks and means cooperating with said stress distributing supports and car body for locking the same in position upon the supplemental tracks for the purpose of permitting the gun to be fired from the body at any angle or inclination.

9. The combination of a railroad track, a

- car body, a gun mounted thereon, the car body being provided with wheeled trucks, supplemental recoil shock-receiving rails mounted parallel with the main railroad track, movable shoes carried by the car body adapted to engage the supplemental supporting rails, and means for moving the shoes into engagement with said supplemental supporting rails to relieve the wheeled trucks of the recoil shock. 10. The combination with a railroad track, of a car body provided with wheeled trucks movable thereover, supplemental supporting tracks adjacent to the railroad track, wheels 15 adapted to cooperate with said supplemental tracks to assist in transporting the car body thereon, movable shoe members carried by the car body, and means for forcing the shoes into frictional engagement with the supplemental tracks. 11. The combination of a railroad track, a car including a body and wheeled trucks therefor, a gun mounted on the car body, supplemental recoil shock-receiving grooved tracks adjacent the railroad track, said car body being provided with movable shoes, and means for bringing the shoes into engagement with the supplemental grooved tracks to relieve the wheeled trucks of the recoil shock. 12. In combination with a railroad, a car body movable thereover, supplemental supporting rails adjacent the main rails of the railroad and means on said car body for engaging said supplemental rails, an abutment, and compressed air means carried at the end of the car body adapted to cooperate with the abutment to dislodge the car body from its position upon the supplemental rails. 13. The combination with a railway car having transporting wheels and adapted to support ordnance under firing conditions, of means other than the car wheels for slidably supporting the car under recoil action incident to firing of the ordnance, and means for locking the car against such sliding movement. 14. The combination with a railway car having transporting wheels and adapted to support ordnance under firing conditions, of slidable supporting means other than the car wheels operatively associated with the car permitting bodily yield of the car under recoil action incident to firing the ordnance, and means for restraining movement of said slidable supporting means. 15. The combination with a railway car having transporting wheels and adapted to support ordnance under firing conditions, of slidable supporting means other than the car wheels operatively associated with the car permitted bodily yield of the car under recoil action incident to firing the ordnance, and means for preventing movement of said slidable supporting means to convert the same into stationary supports when an unyielding car is desired. 16. The combination with a railway car having transporting wheels and adapted to support ordnance under firing conditions, of means other than the car wheels operatively associated with the car for slidably supporting the same under the action of the recoil incident to firing the ordnance in one direction in relation to the car and constituting lateral resistance means when the ordnance is fired in another direction with relation to the car. 17. The combination with a railway car having transporting wheels and adapted to support ordnance under firing conditions, of means other than the car wheels operatively associated with the car for slidably supporting the same under the action of the recoil incident to firing the ordnance in one direction in relation to the car and constituting lateral resistance means when the ordnance is fired in another direction with relation to the car, and the ordnance mounted on said car adapted to fire either lengthwise thereof or turned to fire at an angle to the longitudinal axis of the car. 18. The combination with a railway car having transporting wheels and adapted to support ordnance under firing conditions, of means other than the car wheels operatively associated with the car for slidably supporting the same under recoil action incident to firing the ordnance, and a rail to cooperate with said means, said means being formed to have an interfitting engagement with said rail to constitute lateral resistance means to resist recoil action angularly with reference to the longitudinal axis of the car. 19. The combination with a railway car having transporting wheels and adapted to support ordnance under firing conditions, of means other than the car wheels operatively associated with the car for supporting the same under recoil action incident to firing the ordnance, and a rail to cooperate with said means, said means being formed to have an interfitting engagement with said rail to constitute lateral resistance means to resist recoil action angularly with reference to the longitudinal axis of the car. 20. The combination with a railway car having transporting wheels and adapted to support ordnance under firing conditions, of means other than the car wheels operatively associated with the car for slidably supporting the same under recoil action incident to firing the ordnance, and a rail to cooperate with said means, said means being formed to have an interfitting engagement with said rail to constitute lateral resistance means to resist recoil action angularly with reference to the longitudinal axis of the car, and the rail formed in cross section complementary to

said supporting means to accomplish the interfitting stated.

21. The combination with a railway car having transporting wheels and adapted to support ordnance under firing conditions, of means other than the car wheels, operatively associated with the car for supporting the same under recoil action incident to firing the ordnance, and a rail to cooperate with said means, said means being formed to have an interfitting engagement with said rail to constitute lateral resistance means to resist recoil action angularly with reference to the longitudinal axis of the car, and the rail formed in cross section complementary to said supporting means to accomplish the interfitting stated.

22. The combination with a railway car having transporting wheels and adapted to support ordnance under firing conditions, of means other than the car wheels operatively associated therewith for both slidably supporting the car under recoil action incident to firing the ordnance and for constituting a resisting means opposed to the recoil action in line with the direction of firing of the gun angularly with reference to the longitudinal axis of the car.

23. The combination with a railroad incapable in itself of resisting the firing strains of ordnance, of a car having wheels adapted to traverse said railroad and capable of supporting ordnance under firing conditions, ordnance on said car, supporting means provided adjacent to said railroad, means for anchoring the car thereto to resist recoil shocks incident to firing the ordnance, and supporting means other than the car wheels carried by the car to permit firing the ordnance when the car is disengaged from said first supporting means.

24. The combination with a railroad incapable in itself of resisting the firing strains of ordnance, of a car having wheels adapted to traverse said railroad and capable of supporting ordnance under firing conditions, ordnance on said car, supporting means provided adjacent to said railroad, means for anchoring the car thereto to resist recoil shocks incident to firing the ordnance, and supporting means other than the car wheels to permit firing the ordnance when the car is disengaged from said first supporting means.

25. The combination of a railroad car, a gun on the car, adjustable supporting means mounted on the car to be lowered into slidable contact with stationary rails and thereby relieve the car trucks from the shock of recoil.

26. The combination of a railroad car, a gun on the car, adjustable supporting means mounted on the car to be lowered into slidable contact with stationary rails and thereby relieve the car trucks from the shock

of recoil, and means for locking the car against such sliding movement.

27. A railroad gun carriage provided with trucks for running on a railroad track, a gun mounted on said carriage to be fired therefrom, and a plurality of track-engaging members movably mounted on said carriage and movable into position to transmit forces of the gun recoil to a track by sliding contact therewith and to relieve the truck wheels and axles of said forces.

28. A railroad gun carriage provided with trucks for running on a railroad track, a gun mounted on said carriage to be fired therefrom, slideways extending longitudinally of the railroad track, and a plurality of members movably mounted on said carriage and movable into engagement with said slideways to transmit forces of the gun recoil to said slideways by sliding contact therewith and to relieve the truck wheels and axles of said forces.

29. A railroad gun carriage provided with trucks for running on a railroad track, a gun mounted on said carriage to be fired therefrom, a track-engaging member movably mounted on said carriage, and means for moving said member into and out of engagement with a track to transmit forces of the gun recoil to said track by sliding contact therewith and to relieve the truck wheels and axles of said forces.

30. A railroad gun carriage provided with trucks for running on a railroad track, a gun mounted on said carriage having means for adjusting the gun relative to the carriage for azimuth pointing and permitting firing of the gun from the carriage, and a track-engaging means mounted on said carriage to be movable into position to transmit forces of the gun recoil to a track by sliding contact therewith and to relieve the truck wheels and axles of said forces.

31. A railroad gun carriage provided with trucks for running on a railroad track, a gun mounted on said carriage having means for adjusting the gun relative to the carriage for both azimuth pointing and angular elevation and permitting firing of the gun from the carriage, and a track-engaging means mounted on said carriage to be movable into position to transmit forces of the gun recoil to a track by sliding contact therewith and to relieve the truck wheels and axles of said forces.

32. A railroad gun carriage provided with trucks for running on a railroad track, a gun mounted on said carriage, means for adjusting the gun with reference to the carriage for azimuth pointing thereof and enabling the firing of the gun from the carriage, of means at opposite sides of the carriage movably mounted with respect to said carriage to be placed in position to transmit forces of the gun recoil to the track members

by sliding contact therewith and to relieve the truck wheels and axles of said forces when the gun is fired in either direction tending laterally of the carriage.

5 33. A railroad gun carriage provided with trucks for running on a railroad track, a gun mounted on said carriage to be fired therefrom, and track-engaging means op-

eratively associated with said carriage for sliding contact with a track independent of said railroad track to transmit forces of gun recoil thereto.

In testimony whereof I have hereunto set my hand and seal this 26th day of May, 1917.

LAWRENCE W. LUELLEN.
